STOKER CONSTRUCTION

William Thompson Hanna, Cincinnati, Ohio

Original application April 5, 1929, Serial No. 352,760. Divided and this application August 1, 1930, Serial No. 472,347

6 Claims. (Cl. 110—101)

This invention relates to stokers in general but more particularly to stokers for use on locomotives and the like.

One of the objects of the invention is to provide a simple, compact and sturdy stoker mechanism which will effectively convey the fuel from the coal hopper in the tender to the fire box of the locomotive and insure proper distribution of the same therein.

Another object is to insure free movement of the fuel throughout the stoker mechanism.

Another object of the invention is to provide a stoker mechanism of the character above described in which there is an improved operation, and which is more effective to spread the fuel more evenly over the fire bed of the fire box. Other objects will be in part obvious and in part pointed out hereinafter.

This application is a division of my copending application Serial No. 352,760, filed April 5, 1929, now issued into Patent No. 1,961,215.

The invention accordingly consists in the features of construction, combinations of elements and arrangements of parts which will be exemplified in the mechanism hereinafter described and the scope of the application of which will be indicated in the following claims.

In the accompanying drawings is shown one of the various possible embodiments of the invention in which:

Fig. 1 is a side elevation partially in section;

Fig. 2 is an enlarged longitudinal sectional view of the portion of the stoker mechanism adjacent the fire box but with the fuel propelling or conditioning devices removed from the housing.

Fig. 3 is a sectional view on the line 3—3 of Fig. 2;

Fig. 4 is a sectional view on the line 4—4 of Fig. 2;

Fig. 5 is an ideal section of the fuel propelling and conditioning device of Figure 3, taken on line 5—5 of Figure 3; and

Fig. 6 is a transverse view on the line 6—6 of Fig. 2.

Referring to the drawings, 10 represents the back head of a locomotive fire box having the usual grate bars 11 and firing opening 12. Embracing this opening and rigidly mounted on the outer face of the back head 10 is a fuel supply housing 13 having, at its lower end, a fuel supply conduit or extension 14 merging therewith. This extension encompasses the delivery end of a transfer conveyor 15 which is rotatively supported in a cylindrical conduit 16. The forward

end of the conduit 16 is provided with a universal connection with the extension 14 below the deck 17 of the locomotive. This connection comprises a spherical shaped member 16^a secured to the end of the conduit 16 and journaled in a spherical shaped recess 14^a in the end of the extension 14.

The conveyor 15 has an operative connection (not shown) with a conveyor 18 mounted for rotation within the tender hopper 19 below the tender deck 20. The conveyor 18 in turn is operatively connected with a power device 21, located on the locomotive and this connection comprises a telescopic shaft 22, universally connected at 23 with the power device and at 24 with a shaft 25. This shaft 25 is journaled upon the tender hopper and has at its rear end a gear (not shown) which meshes with a gear 26 (shown in dotted lines) secured to the rear end of the conveyor 18.

The contour of the housing 13 and its extension 14 is designed to receive the fuel from the delivery end of the conveyor 15, and to elevate it in a substantially direct line of flow from the mouth 37 of the extension 14 to the firing opening 12. In other words, there is an alignment between the mouth 37 and the firing opening 12. This straight line of flow has many advantages, such as increasing the efficiency of the stoker mechanism by increasing the ease and freedom with which the fuel moves through the housing 13.

This freedom of flow is further enhanced by the particular construction of the extension 14.

The cross-section of the housing extension 14 and the cross-section of the housing 13 where it joins the extension 14 as at 37 is substantially circular in contour, thus giving, in effect, a circular conduit through which the fuel is elevated to the firing opening 12. The cross-sectional area of the extension 14 is the smallest at that portion designated 14^b, this portion being substantially of the same diameter as the inside diameter of the member 16^a. Immediately forward of the point 14^b, the extension 14 is suddenly enlarged on the top half thereof as shown in Figs. 2 and 6. This feature serves to give the volume of fuel a sudden relief as it begins its upward movement through the conduit and very materially facilitates the elevation of the fuel. Further, the cross-sectional dimension of the conduit forward and upward from the point 14^b has an increasing diameter which, in effect, gives the upper end of the fuel supply conduit a flaring, as shown at 37.

To further assist in the freedom of flow of the fuel through the housing 13 there are provided in the walls of the housing 13 fuel supporting recesses or conically shaped ledges 33 which, as shown in the present embodiment, slope forwardly and upwardly toward the firing opening 12. For purposes to be described hereinafter, the fuel supporting recesses 33 are conically shaped and converge to the apex of the imaginary cones 5 embracing the recesses pointing toward the firing opening 12. The forward ends 33^b of the recesses 33 meet at a point 38 just in the rear of the lower edge of the firing opening 12. The forward and upper portion of the mouth 37 also 10 meets the two ends 33^b at point 38. The mouth 37 of the extension 14 intersects or merges with the recesses 33 along edges 33^a, as shown more clearly in Figures 3 and 4. The combination of 15 the flaring mouth section 37 of the extension 14 with the edges 33^a and the recesses 33 provides many new and highly advantageous results. For 20 example, a rising column of fuel in the extension 14 is allowed to expand toward the sides of the housing 13 over the flared mouth 37 whence it 25 spills over the edges 33^a, and drops on to the fuel supporting recesses 33. In this way, any tendency 30 of the fuel to mound or pile up in front of the center of the firing opening 12 is offset, and thus the back pressure upon the rising column of fuel, caused by excessive mounding of fuel thereof, is eliminated.

To further expedite the even, uninterrupted and distributed flow of fuel from said fuel supply housing through the firing opening 12, I provide in the housing 13 fuel spreading or fuel conditioning means 27 and 28 respectively, each means comprising, in the present embodiment, a rotatable spiral tapered vane or worm. Each worm 27 and 28 is positioned in its respective 35 recess 33, and suitably journaled in cap-plate 29 or 30, forming part of the wall of the housing 13. The recesses 33 are so constructed, and their respective rotary vanes 27 and 28 so positioned, that the portions of the recesses or ledges 33, 40 generally indicated at 39, which are remote from the firing opening 12, are curved to conform with a conically shaped surface containing the outer periphery of the respective vanes 27 and 28. However, those portions of the recesses 33 adjacent 45 the edges 33^a are curved eccentrically about a surface containing the outer periphery of the vanes, as shown in Figure 5. By providing this eccentricity between the vanes 27 and 28 in their respective recesses 33, fuel that flows over the edges 33^a on to the ledges 33 from the extension 14 cannot jam between the hub of the vane and 50 the surface of the ledge, but readily passes on around.

With the construction shown in the present embodiment I find it particularly advantageous to position the axes of the vanes 27 and 28 so that the vanes converge laterally and upwardly toward the center line 38 at the lower edge of the firing opening 12. Under certain conditions of operation, however, I may find it advantageous to arrange the axes in a parallel arrangement with respect to each other, or in an arrangement whereby the axes diverge from each other.

Rotary motion is imparted to the vanes 27 and 70 28 through suitable gearing, (not shown) within the housing 13, and driven by the telescopic shafts 32 which are universally connected each at one end with such gearing and at the other end with the power device 21, or in any other manner that 75 may be found most expedient.

The fuel propelling and conditioning mechanism, comprising the spiral vanes 27 and 28, has associated therewith a blast chamber 34 and a distributing plate 35 lying within the firing opening 12 and these serve to scatter the fuel efficiently to all parts of the fire bed. The tender hopper 19 is equipped, at its delivery end, with a powerful fuel crushing device 36.

In the operation of this stoker mechanism the coal passes through the deck 20 of the tender 10 into the trough of the tender hopper 19 and is moved therein by means of the conveyer 18, into the crushing device 36 wherein the abnormally large lumps of fuel are cracked and broken up to normal size before discharge from the tender 15 hopper. The fuel is then delivered to the transfer conveyer 15 by which it is transported and delivered into the ascending conduit formed by the housing extension 14 and the lower portion of the housing 13. At this point the fuel in the 20 mouth portion 37 of the extension 14, still being pushed on by the oncoming fuel beneath, tends to fall away at the sides due to the flaring at the mouth 37 and flows over the edges 33^a on to the recesses 33 where it encounters the vanes 27 25 and 28 which serve to disintegrate and spread the rising column of fuel over the fuel conditioning housing 13 and cause the loose fuel to pass through the firing opening in a continuous uniform stream and fall upon the plate 35. It is then 30 scattered over the fire by means of blasts of steam emitting from the jets of the blast chamber 34.

It will be recognized that the form of the passage through which the fuel is elevated to the vanes 27 and 28 is such, particularly at the top of the said passage on the right hand and left hand sides, that the rising column of fuel is permitted to spill over into the path of the outer ends of the vanes and the effect of this is to decrease the tendency of the fuel to mound or pile up at 40 the center in front of the vanes as might be the case with certain conditions of fuel. Furthermore, it is evident that the relationship between the surface of each ledge 33 and its respective vane is such that the spacing between the ledge 45 and vane gradually increases from the edges 33^a of the ledge around to the forward part thereof as generally indicated at 40, Figure 5. With this construction tendency of lumps of fuel to become wedged between the hub portion of the 50 vanes 27 and 28 and their respective ledges, or between the outer peripheries of said vanes and their respective edges is avoided.

It will thus be seen that there is provided a construction of an essentially practical nature in 55 which the several objects of the invention are attained.

While I have shown and described a particular construction embodying the novel features of the invention, it is to be understood that the same 60 is for illustration only and it will be obvious that the construction and arrangement of parts may be variously modified and altered without departing from the spirit and scope of the invention as set forth in the appended claims.

I claim:

1. In a stoker mechanism, the combination with a fire box having a fuel entrance of a housing embracing the fuel entrance and formed to provide a ledge in the rear of the fire box opening to receive fuel delivered thereto, and a spiral vane rotatably mounted in the housing and extending over the ledge to break up the fuel delivered to the ledge and feed it to the fire box, the portion of the ledge remote from the fire box being curved 75

to conform to the periphery of the spiral vane, and the portion of the ledge adjacent the fire box being curved eccentrically to the periphery of the spiral vane to facilitate the feeding of the fuel to the fire box, and means for delivering the fuel upwardly and over that portion of the ledge remote from the fire box.

2. In a stoker mechanism for a fire box having a back head and a firing opening in said back head, in combination, a fuel conditioning housing communicating with said firing opening and having a fuel supply conduit opening thereinto, said fuel conditioning housing having a plurality of elongated concave fuel supporting recesses formed therein; and a plurality of fuel loosening screws mounted in said housing, each fuel loosening screw having its lower portion embraced by one of said recesses, at least a portion of the surface of each of said recesses being concentric with and parallel to a surface containing the outer surface of the fuel loosening screw located therein, and another portion of the surface of each of said recesses being curved eccentrically about a surface containing the outer surface of its respective fuel loosening screw whereby fuel entering between said fuel loosening screws and their respective recesses will not become wedged therebetween.

3. In a stoker mechanism, the combination with a locomotive fire box having a firing opening and a tender of a housing communicating with the firing opening, transfer mechanism arranged to convey fuel from the tender to the housing, a rotatable spiral vane mounted within the housing to receive fuel from said transfer mechanism, a portion of said housing below and rearwardly of said vane being in the form of a circular conduit, the diameter of which increases as it approaches the vane, the upper end of said conduit flaring immediately below said vane, and a concave ledge formed continuously with said conduit intermediate said conduit and said firing opening and embracing the lower side of said vane and being curved eccentrically about the side thereof adjacent the firing opening, whereby fuel passing upwardly through said conduit may flow onto said ledge into the radius of said vane.

4. In a stoker mechanism, the combination with a fire box having a fuel entrance, of a conduit provided with means for moving fuel from a source of fuel supply to said entrance and having a recessed fuel supporting ledge formed therein and positioned adjacent and to the rear of said entrance,

means for distributing fuel fed to said entrance upon and over the fire, and fuel conditioning and regulating means comprising a rotary worm associated with said conduit and fuel entrance and interposed between said fuel moving means and said distributing means for moving fuel across the fuel supporting ledge to transform the forced fuel into form relatively thinner than the bulk of fuel in the conduit and to regulate the presentation of fuel to the distributing means, said rotary worm being positioned in part in said recessed ledge, and the ledge being curved eccentrically with respect to the periphery of the rotary worm to provide increasing space between the periphery and surface from the point where fuel first moves onto the surface to the point where it leaves the surface.

5. In a stoker mechanism in combination a fire box having a firing opening, a fuel transfer conduit for conveying fuel from a source of supply to said firing opening, a curved recessed fuel supporting surface in said conduit and extending crosswise thereof over which fuel flows in passing to said firing opening, and a conically shaped rotatable fuel moving worm mounted in said conduit above said fuel supporting surface and extending into the recessed portion thereof to move fuel thereacross to said firing opening, and the space between the outer periphery of said rotary worm and said surface constantly increasing from the point where fuel first moves onto said surface to the point where the fuel leaves said surface whereby the possibility of fuel becoming wedged between said worm and surface as it moves thereacross is eliminated.

6. In a stoker mechanism, the combination with a fire box having a firing opening, of a housing communicating with said opening and having a fuel supply inlet, said housing also having an elongated concave fuel supporting recess formed in a wall thereof and generally sloping upwardly toward said firing opening; a tapered spiral vane rotatably mounted in said housing and positioned in part in said recess, the portion of said recess remote from said fire box being curved to conform to a surface containing the periphery of the spiral vane and the portion of the recess immediately adjacent the fire box being curved eccentrically to the surface containing the periphery of the spiral vane, and means for delivering the fuel upwardly and over that portion of the recess remote from the fire box.

WILLIAM THOMPSON HANNA.
